CLAIM

The ornamental design for a railroad car combined vented hatch cover protector and gasket, as shown and described.

DESCRIPTION

This application is related to the following commonly owned co-pending patent application: U.S. application Ser. No. 16/380,033, entitled "Railroad Car Vented Hatch Cover Assembly Including a Replaceable Combined Vented Hatch Cover Protector and Gasket".

FIG. 1 is a bottom perspective view of a railroad car combined vented hatch cover protector and gasket of our new design, the opposite side being a mirror image thereof. FIG. 2 is a top perspective view of the railroad car combined vented hatch cover protector and gasket of FIG. 1, the opposition side being a mirror image thereof.

FIG. 3 is a first side view of the railroad car combined vented hatch cover protector and gasket of FIG. 1, the opposite side view being a mirror image thereof.

FIG. 4 is a second side view of the railroad car combined vented hatch cover protector and gasket of FIG. 1, the opposite side view being a mirror image thereof.

FIG. 5 is a top plan view of the railroad car combined vented hatch cover protector and gasket of FIG. 1.

FIG. 6 is a bottom plan view of the railroad car combined vented hatch cover protector and gasket of FIG. 1.

FIG. 7 is a top perspective view of a cross-section of the railroad car combined vented hatch cover protector and gasket of FIG. 1, the cross-section taken across line 7-7 of FIG. 2.

FIG. 8 is a cross-sectional view of the railroad car combined vented hatch cover protector and gasket of FIG. 1, the cross-section taken across line 7-7 of FIG. 2; and,

FIG. 9 is an enlarged fragmentary cross-sectional view of the railroad car combined vented hatch cover protector and gasket of FIG. 1, the cross-section taken across line 7-7 of FIG. 2.

The broken lines shown in the views depict environmental subject matter only and form no part of the claimed design.
